FLAT BLOCK PRINTING MACHINE

John Howard Chadwick, Franklin Park, and Charles C. Willis, Bound Brook, N. J., assignors to John Waldron Corporation, New Brunswick, N. J., a corporation of New Jersey

Application November 24, 1934, Serial No. 754,606

7 Claims. (Cl. 101—199)

This invention relates to block printing machines of the type illustrated in the patent granted on December 25th, 1917, No. 1,251,144, to W. H. Waldron.

5 In the aforesaid Waldron patent the pan motion drive mechanism for supplying color to the printing blocks is duplicated and located at both ends of the machine on machines exceeding eighteen heads. Such a machine may 10 vary and may reach a considerable length as well as a considerable width. It may run up to thirty-six or more sections to provide the necessary printing heads for the coloring desired. The enlargement of the previous type is costly. 15 In addition, difficulty is sometimes experienced in the failure of the two drives to synchronize and it is essential for the reciprocating movement to be of such a nature as to be as even as possible in order to prevent disturbance of 20 the color in the color pans and to insure proper inking of the printing heads.

In the former types of machine the cross shafts were passed directly through the worm reducer and in the event of a smashup it was difficult 25 to remove the long shaft from the reducer. To obviate this difficulty, couplings were subsequently inserted on each side of the reducer. This added to the expense and created the danger of the cams on the opposite ends of the 30 shafts not having exactly the same setting.

One of the objects of our invention is to improve the drive on a flat block printing machine by providing driving means centrally of the machine thereby reducing the length of the machine 35 in consequence of the removal of the drive from each end and providing the drive in the center space of the machine which is also utilized for inspection of the ground printing before the top design is put on thereby making the same space serve both for the drive and for the inspection of the goods.

Another object of the invention is to improve the satisfactory working qualities of the machine by dispensing with a dual drive and substituting 40 a single drive thereby assuring absolute synchronization.

Still another object of the invention is an improved drive wherein in the event of breakdowns, replacements can be quickly made and breakage, if any, will occur in connection with simple parts thereby avoiding long shut downs and decreased maintenance costs.

A still further object of the invention is to 45 provide a flat block printing machine that may

be built up in sections and readily enlarged by the simple addition of sections.

Other objects will appear more fully herein-after.

Referring to the drawings:

Figure 1 is a view in side elevation of the center portion of a flat block printing machine embodying the principles of our invention.

Figure 2 is a view in side elevation with parts removed of the center portion of the flat block 10 printing machine embodying the principles of our invention.

Figure 3 is a partial plan view of the center drive and quick removable cam shafts.

As this type of machine has been fully described in the Waldron Patent No. 1,251,144, it is only necessary to describe the improvements embodying the principles of our invention in connection therewith.

The longitudinal side frames 1 of the machine 20 have upper beams 2 and lower beams 3 spaced apart by columns 4. Wheels 5 carried by frames 1 are adapted to roll on track 6 to permit movement of the machine from in front of one drying chamber to another. The printing heads 7 25 are similar to the Waldron structure and are inked in the customary way by carriages 8 which are reciprocated back and forth when the printing heads are raised by the cam shafts.

In the drive that we have invented the main 30 motor 9 through gearing 10, 11 and chain 12, drives the main drive shaft 13. A heavy worm reducer 14 transmits the drive from shaft 13 to stud 15 carrying gear 16 meshing with gear 17 on cross shaft 18. On each end of 18 are 35 drivers 19 each carrying cam rolls 20. The cam rolls 20 operate in the two slots 21 of the spider 22, the latter being mounted on cross shaft 22'. The drive is the same on both sides. Shaft 18 drives shafts 22 and 29 through a train of four 40 gears 23, 24, 25, 26. Gear 23 is carried by shaft 18 and gears 24, 25, are carried by studs 27, 28, while gear 26 is secured to shaft 29. Shaft 18 drives shaft 29 at the same rate of speed as shaft 18. Shaft 29 carries driver 30 and cam roller 31, 45 the latter also operating in one of the slots 21 of spider 22. At the top of spider 22 is a stud 33 connected through link 34 to gear 35. Gear 35 is carried by shaft 36. Gear 35 meshes with a lower stationary rack 37 and at the same 50 time meshes with the movable rack 38 above gear 35. Mounted at each end of shaft 3 are guide blocks 46 operating between guides 47 to maintain gear 35 in its predetermined path between the racks in order to obtain the desired 55

increase in movement of the carriages 8. Mov-
able rack 38 is connected to two slides 39 to
which the carriages 8 are secured by pins or in
any other well known manner. To the end of
5 link 34 is connected air piston 40 operating in
cylinder 41 to assist in stopping without jarring
the large weight of the pan sections. By this
particular form of drive it is possible to multiply
the pan movement by the use of the two racks.

10 The arrangement of the drive is of considerable
importance. The worm reducers 14, 14', etc.,
are all mounted on the main drive shaft 13 with
intervening couplings 42 and a gear drive is uti-
lized from the reducers 14, 14', to the cross shafts
15 18, 18', 18'', etc., as shown by the gears 43, 44, 43',
44'. The cross drive shafts are arranged with
cap bearings 45. With this arrangement in the
case of breakdown or trouble on the machine
which may require the removal of a cross shaft it
20 is necessary to remove only the two caps 45 from
frames 1 when the entire shaft may be taken out
of the machine in one piece without breaking
couplings or removing cam through any reducer.

By this arrangement in the case of a jam of
25 the pan motion any breakage in the drive is
caused to occur in the cam shafts or gears 43, 44,
which have been designed to be readily removed.
The cam shafts 18', 18'', operate the individual
printing head.

30 In the old type of machine the shafts went
right through the side frame, the bushings being
set in these frames. The breakdowns generally
occurred from the slide sticking on one side of the
35 machine, as the top weight and slides drop by
gravity until they are again locked into printing
position by the outside plate on the cam. Also
trouble sometimes occurs from interference
between the pan and the block and when this
40 occurs it generally means a bent or twisted cross
shaft and in the case of the old machine an
expensive and difficult form of repair.

The number of cross shafts to operate printing
heads is dependent upon the number of sections
45 required for the desired number of colors and
obviously as many reducers may be coupled into
the main drive shaft 13 as will likewise be re-
quired. Such additions are added on both sides
of the center drive and require no change in the
driving mechanism, but only substitution of
50 longer sliding bars for the carriages 8.

It will thus be seen that we have invented a
drive for flat block printing machines wherein
the case of breakdown the parts can be readily
55 replaced or repaired thereby reducing the time
the machine is out of commission and also re-
ducing the maintenance costs since the cam
shafts are more likely to be twisted than the other
elements of the drive. Also that economy of
60 space is secured with a better drive that is sim-
pler, less costly to manufacture, cheaper to oper-
ate and consuming less power than the dual
driving means heretofore used.

What we claim is:

1. In a flat block printing machine, color pans,

bars carrying the pans, means centrally of the
machine for multiplying the movement of the
pans, said means including a stationary rack and
a movable rack above the stationary rack, a gear
between said racks and meshing with both of
5 them, means for motivating said gear and bars
carrying the pans connected to the movable rack.

2. In a flat block printing machine, a frame,
printing heads, reciprocating pans for inking said
printing heads, means for reciprocating said ink-
10 ing pans, said means comprising a sliding bar,
means for motivating said bar, said means com-
prising a movable rack and a stationary rack, a
gear meshing with both racks, a link connected
15 to said gear and to a spider, slots in said spider,
rolls operating in said slots forming a Geneva
motion, said rolls carried by drivers, and means
for operating said drivers.

3. In a flat block printing machine, a sectional
frame, printing heads carried by each section of
20 said frame, reciprocating carriages for inking
said printing heads, sliding bars for motivating
said printing pans, connections between said pans
and said sliding bars, central means for recipro-
cating said sliding bars, said means comprising a
25 movable rack and a stationary rack, an inter-
vening gear meshing with both racks, means for
rocking said gear and driving means for actuating
said rocking means.

4. In a flat block printing machine, a series of
color pans mounted on reciprocating bars, a re-
ciprocating rack connected to said bars, a sta-
tionary rack mounted beneath the reciprocating
35 rack, an intervening gear meshing with both
racks, means for reciprocating said gear, said
means consisting of a link connected to the top of
a lever, the bottom of said lever having two open
end slots cut radially and on opposite sides of its
fulcrum point, rolls operating in said slots from
a crank motion, and means for driving said
40 cranks.

5. In a flat block printing machine, a series of
color pans mounted on reciprocating bars, a re-
ciprocating rack connected to said bars centrally
45 of said machine, a stationary rack mounted be-
neath the reciprocating rack, an intervening
gear meshing with both racks, means for recipro-
cating said gear one-half the movement of the
reciprocating rack.

6. In a flat block printing machine, a series of
color pans secured to reciprocating bars, a recip-
rocating rack connected to said bars, a stationary
rack mounted beneath said reciprocating rack,
an intervening gear for multiplying the move-
55 ment of the reciprocating rack in combination
with a Geneva drive for reciprocating said gear.

7. In a flat block printing machine, a series of
pans, a central drive means for reciprocating
said pans, said drive means comprising in com-
bination a plurality of racks with an intervening
60 gear operated by a Geneva action.

JOHN HOWARD CHADWICK.
CHARLES C. WILLIS.
